UNITED STATES PATENT OFFICE.

HENRY WEBER, OF CHICAGO, ILLINOIS, ASSIGNOR TO LATHAM MACHINERY COMPANY,
OF CHICAGO, ILLINOIS, A CORPORATION OF ILLINOIS.

ADJUSTABLE GUIDE FOR STAPLING AND RIVETING MACHINES.

1,150,912.

Specification of Letters Patent. Patented Aug. 24, 1915.

Application filed September 27, 1912. Serial No. 722,574.

To all whom it may concern:

Be it known that I, HENRY WEBER, a citizen of the United States, residing at Chicago, in the county of Cook and State of Illinois, have invented certain new and useful Improvements in Adjustable Guides for Stapling and Riveting Machines, of which the following is a specification.

This invention relates to novel and useful improvements in attachments for stapling, riveting and wire stitching machines and is designed to provide a means whereby the work may be fed and guided directly through the machine in such a manner that 15 the overlapping edges thereof may be properly located.

In the manufacture of boxes or cartons the edges thereof are overlapped and are riveted or stitched together, the under edge being 20 provided with a flap, the standard width of which is substantially $1\frac{1}{2}$ inches, said flap being separated from the body of the carton by a crease or score which hinges the flap to said body. It will, therefore, be seen that 25 it is essential that the upper edge of the overlapping edges must terminate at the crease or score as aforesaid, in order that the same may perform its function, *i. e.*, form a hinge connection between the sections of the 30 carton connected by the overlapping edges.

Although the standard width of the flaps heretofore mentioned is $1\frac{1}{2}$ inches, the same varies considerably and it is therefore, necessary to provide an adjustable guide whereby 35 the upper edge of the overlapping edges may be located in such a manner that the same will terminate adjacent to the crease or score aforesaid.

It is the object of the present invention to 40 provide such an adjustable guide, thus insuring accuracy in the overlapping the edges and insuring a machine which will stitch said overlapping edges without interfering with or detracting from the functions of the 45 score or crease.

Furthermore, this invention contemplates the construction of such an adjustable guide heretofore referred to, and in addition thereto, the provision of auxiliary guides which 50 will insure the movement of the carton or box from the guide under the stitching or stapling head in such a manner that the passage of said carton or box will in no way

be obstructed. These auxiliary guides are also adapted to prevent the carton or card- 55 board, or material of which the carton or box is constructed from curling upward on contacting with the stitching or stapling head.

With the above and other objects in view 60 this invention consists in the construction, combination and arrangement of parts, all as hereinafter more fully described, claimed and illustrated in the annexed drawings 65 wherein.

Figure 1 is a fragmentary top plan view of the work table of a stapling or riveting machine, illustrating the improved feed guide forming the subject matter of the 70 present invention. Fig. 2 is a transverse section taken along line 2—2 of Fig. 1. Fig. 3 is a vertical section taken through the feed guide along line 3—3 of Fig. 2.

The guide forming the subject matter of the present invention, comprises an adjustable attachment of the guide forming the subject matter of my pending application filed February 7th, 1912, Serial No. 676090, and constitutes a guide plate carried by said 75 guide and arranged at an acute angle thereto, said guide plate being movable horizontally over said guide referred to.

Reference being made more particularly to the drawings, 10 indicates the table of a wire stitching or stapling machine particularly adapted to use in connection with cartons or boxes, said table being pierced medially by the anvil bar 11. Superposed above the anvil bar 11, is a head 12, of any suitable or standard construction, said head 80 adapted to be alined with the guide herein- 85 after more fully described at all times. The head 12 is in most circumstances supported and carried by a goose neck (not shown), said goose neck likewise carrying a support- 90 ing frame 13 which carries a horizontal plate 14, which rests parallel to the table 10.

Secured to the underside of the plate 14, is a vertical bracket 15, which terminates at its lower end in a horizontally arranged 100 portion 16, said horizontally arranged portion being pivoted between the uprights 17, formed on or otherwise secured to a horizontal web 18. The outer edge of this horizontal web terminates a vertical web 19, said 105 vertical web connecting the horizontal web

18 to a work supporting guide bar 20, which is reduced in width as at 21 adjacent to the head 12, said reduced portion terminating in an anvil 22 which is supported above and 5 coincides with the anvil bar 11.

It will therefore, be seen that the guide heretofore described, is slightly pivoted on the horizontal portion of the bracket 15 in order that the reduced portion 21 and the 10 anvil 22 carried thereby may be provided with a slight movement.

All of the foregoing construction is recited and claimed in the heretofore referred to pending application.

15 A bracket 23 is arranged above the web 18 and has its inner terminal bent upwardly to form an attaching portion 24 which is secured to the bracket 15 in such a manner that the bracket 23 is arranged at an acute 20 angle to the plane of the web 18 and the work supporting and guiding bar 20. The bracket 23 is slotted as at 25, said slot providing the means whereby the guiding plate forming the subject matter of the present 25 invention may be adjusted to and from the bracket 15 as hereinafter more fully described.

A plate 26 is secured to the bracket 23 by means of an elongated lug or projection 30 27 formed on said plate which is reciprocatingly and adjustably received in slot 25 of the bracket 23. The plate 26 is secured to the underside of the bracket 23 and the upper edge of the projection or lug 27 rests 35 flush with the upper surface of the bracket 23. This lug or projection 27 carries a threaded spindle 28, upon which is mounted a lock nut 29, said lock nut being provided with a handle or operating member 30. The 40 lock nut operates upon the upper surface of the bracket 23, and it will be seen that as the same is threaded downwardly upon the spindle or shank 28, the plate 26 will be drawn upwardly thereby rigidly securing 45 the same in its adjusted position.

The bracket 23 being arranged in such a manner that the plane thereof is at an acute angle to the horizontal plane, it is obvious that the plate 26 will likewise be retained at 50 a similar angle. The forward end of the plate 26 is narrowed and is of substantially the same width as the work supporting and guiding bar 20, while its rear terminal is flared or belled as at 31 to increase the ease 55 with which the material or work may be inserted under the plate 26 as heretofore described.

The inner edge of the plate 26, *i. e.*, the side thereof adjacent to the uprights 17 and 60 bracket 15 is bent downwardly to form a guiding flange 32. The edge of said guiding flange resting throughout its entire length in a horizontal plane, parallel to the web 18 and spaced slightly from the said web.

65 As the plate 26 is adjustably movable rela-

tive to the bracket 23, it will be seen that the guiding flange 32 will likewise be movable with the plate 26, and spaced accordingly from the uprights 17 and the bracket 15.

The inner terminal of the plate 26, 70 namely, the lower terminal thereof located adjacent to the head 12, terminates adjacent to the reduced portion 21 and is provided with a pair of parallel leaf springs arranged in the plane of the plate 26 and extending 75 toward the head 12. The outer ends of the leaf springs 33 are curled or bent upwardly as at 34 to present a rounded surface to the cartons or boxes passing thereunder. The springs 33 insure the guiding of the carton 80 or box under the head 12 and prevent the same from curling upwardly and contacting with said head prior to the passage thereunder.

The carton or box illustrated in the 85 drawings is constructed of a single sheet of material scored at the bends therein, the terminals 35 and 36 being bent inwardly and overlapped. The terminal 35 of the box is scored as at 37, thus forming a flap 38. The 90 body 39 of the carton rests upon the table while the flap 38 rests upon the work supporting and guiding bar 20, and the edge 36 which is adapted to overlap the flap 38 and be stitched thereto, rests upon the web 18 in 95 such a manner that the edge thereof abuts and rests against the flange 32 of plate 26. Inasmuch as the terminal 36 of the carton 39 must abut against or rest adjacent to the scoring 37 the plate 26 is so adjusted that the flange 32 thereof will be located above the scoring 37 thus locating the edge of the terminal 36 adjacent to said scoring. 100

Of course, the construction, formation and number of sections of which the box is 105 constructed has no bearing on the operation of the plate 26.

What is claimed is:

1. In combination, two substantially parallel work supporting plates, a guide flange 110 on one plate near one edge thereof, and a guide flange adjacent the opposite edge of the other plate and adjustable toward and from the first said guide flange, the remaining edges of both said plates being unob- 115 structed.

2. A work support comprising two substantially parallel work supporting plates, positioned one above the other and spaced apart, and a guide member on the upper 120 surface of each supporting plate, the guide on one plate being at the opposite edge of the work support from the guide on the other plate, the two guides being relatively adjustable, and each plate having all its 125 edges, except that near which its guide is positioned, free for the passage of work thereover.

3. A work guide, comprising an upper plate and a lower plate substantially parallel 130

with one another, a guide flange positioned near one edge of the lower plate, the other edges of said plate being unobstructed, a guide member positioned over the upper 5 plate and having a guide flange adjacent said upper plate and near the edge of said plate opposite the first mentioned guide flange, the other edges of said plate being unobstructed, and means for adjusting the 10 last said guide flange toward and from the first said guide flange.

4. A work guide, comprising an upper plate and a lower plate substantially parallel with one another, a guide flange positioned near one edge of the lower plate, the other edges of said plate being unobstructed, a guide member positioned over the upper 15 plate and having a guide flange adjacent said upper plate and near the edge of said plate opposite the first mentioned guide flange, the other edges of said plate being unobstructed, means for adjusting the last 20 said guide flange toward and from the first said guide flange, and means for supporting 25 said work guide, attached to the upper plate

at the side of the plate, near the upper guide flange.

5. A guide for stapling and riveting machines comprising in combination, a bracket, a horizontal extension formed on said 30 bracket, a horizontal web secured to said extension, a guide bar, a vertical web connecting said guide bar to said horizontal web, a secondary bracket secured to said first bracket, and a secondary guide adjust- 35 ably secured to said secondary bracket and superposed above said horizontal web, said secondary guide having a vertical guiding flange formed adjacent to the primary bracket and adjustable to and from the ver- 40 tical web aforesaid.

In testimony whereof I have signed my name to this specification, in the presence of two subscribing witnesses, on this 24th day of September A. D. 1912.

HENRY WEBER.
